Attorney.

UNITED STATES PATENT OFFICE.

WILLIAM L. VOELKER, OF MORTON, PENNSYLVANIA.

TELEGRAPH-RELAY.

SPECIFICATION forming part of Letters Patent No. 237,933, dated February 15, 1881.

Application filed July 16, 1880. (No model.)

To all whom it may concern:

Be it known that I, WILLIAM L. VOELKER, of Morton, in the county of Delaware and State of Pennsylvania, have invented certain new and useful Improvements in Relays, of which the following is a full, clear, and exact description, reference being had to the accompanying drawings, and to the letters of reference marked thereon.

10 My invention has relation to that class of devices used in telegraphy commonly known as "relays," which receive the circuit-current of electricity from the line-wire, and are caused by it to bring into action the power of a local 15 battery for the purpose of re-enforcing the current and performing various work, such as embossing on printing-paper, or the liberation of machinery for the production of sounds.

Relays, as heretofore constructed, consist of 20 an electro-magnet wound with fine wire in the usual manner, which is introduced into the main line and becomes a part of the great conductor from station to station. When the key breaks and closes the circuit the relay receives 25 the voltaic current and becomes magnetized and demagnetized. A delicately-poised lever, having the armature of the magnet attached to it, vibrates backward and forward, bringing together two platinum points, thus breaking 30 and closing a secondary or local circuit, embracing a local battery and a strong electro-magnet. A screw is used to move the magnet-coils backward and forward, so as to adjust the general magnetic power, and a spring 35 retracts the armature after the magnetic attraction which has drawn it forward ceases.

In my improved device I make use of the actuating power of solenoids, or hollow bobbins, for drawing in one or more soft-iron cores, 40 or permanent magnets; and I also employ mercury or any other liquid the specific gravity of which will, when used as in this case, have the effect of breaking the contact which closes the local circuit after the cessation of 45 the electrical impulse that closed the same.

I dispense with the use of an armature and spring for withdrawing the same from the magnet. The regulating-screws may also be dispensed with and two rigid stops put in their 50 place, leaving space enough between for the necessary play of the contact-tongue, the re-

quired position in this case being obtained by the amount of mercury placed in the cistern, or by elevating and depressing the cistern itself.

When permanent magnets are used my device becomes a polarized relay. 55

The drawing represents a vertical axial section of my improved relay, showing all the parts as assembled for use.

A is the base of the instrument, formed of 60 wood or any other suitable non-conducting material, in the usual manner.

B are two hollow bobbins, placed upon the base A and secured thereto.

C is a frame-work of brass extending over 65 the bobbins, and is securely attached to the base by means of screws.

D are two soft-iron cores or magnets fitting into the hollow bobbins, and joined together at the top by means of the iron cross-piece d. 70

E is a platinum wire or rod, extending down between the bobbins through the center of cross-piece d, being fastened rigidly therein. Upon its lower extremity I place a ball, H, of 75 cork, aluminium, or any other very light material; or, if preferred, a hollow bulb of glass may be employed. In the latter case the wire or rod must extend entirely through the bulb, protruding therethrough in order to complete 80 the circuit. At the top of wire E, I attach a contact arm or tongue, e. At F are insulators, made of ivory or other suitable non-conducting material, the wire E playing nicely and freely therein. 85

G is a cistern, of glass or other material, fitted into the base A, under and around the bulb upon the lower extremity of rod E. This cistern is designed to contain mercury for sustaining bulb H, and may be provided with a 90 set screw or nut, I, at bottom, for the purpose of depressing or raising the cistern in order to adjust the rod to a proper position.

Various methods of regulating the height of the mercury will readily suggest themselves. 95 It may be done as above indicated, or by passing a screw through the cup and into the mercury, or by use of an elastic bottom upon the cup, with regulating-screw, after the form adopted in barometers, &c.

K is a set-screw, with insulated point, designed to regulate the height to which rod E 100

may be forced, and L is also a set-screw, provided with a platinum point, to perfect the contact when the arm or tongue e is drawn down by a current of electricity acting upon the magnets to which it is attached. a, a', a², and a³ are binding-screws affixed to the base A, to which are attached the various connections with the line, earth, and local battery.

- When the several parts are assembled for use, the cistern is partially filled with mercury or other liquid, and adjusted to such a position as to allow the bulb H to float therein, thereby raising the rod E, bearing tongue e to such a height as to bear against the insulated point K. One pole of the local battery is attached to binding-screw a', the incoming line-wire to binding-screw a, the outgoing line to a², and the other pole of the local battery and the ground-wire to a³.
- When the current passes over the line, the operation is as follows: It passes through the connections of binding-screw a into and through the bobbins B B, magnetizing the cores D D, thereby drawing them down and making contact between e and L, and putting in operation the local battery, the current of which passes from binding-screw a' up through the framework C, through contact-point L and arm e, down rod E into the mercury cup or cistern, and to line-wire at a², thereby completing the

circuit. Upon the cessation of the current from a, the cores B B are demagnetized and the superior gravity of the mercury forces bulb H up and raises arm e, breaks connection with L, and throws off the local battery. This operation will be repeated with each pulsation of electricity over the line-wire.

Thus it will be seen that when constructed and arranged substantially in accordance with the foregoing description, my improved relay 40 admirably answers the various purposes and objects for which it is intended.

Having now fully described my invention, what I claim as new, and desire to secure by Letters Patent, is—

In a telegraphic relay, base A, hollow bobbins B B, cores D D, rod E, insulators F F, contact-tongue e, bulb or float H, cistern G, for containing mercury or other liquid, screw I, insulated stop K, contact-point L, and frame 50 C, the whole combined and arranged to operate substantially as shown and described.

In testimony that I claim the foregoing I have hereunto set my hand in the presence of two witnesses.

WILLIAM L. VOELKER.
